Fetherstonhaugh & Co.

UNITED STATES PATENT OFFICE.

ALBERT W. ERICKSON, OF NEW YORK, N. Y.

PRINTING RULE.

1,405,570.

Specification of Letters Patent.

Patented Feb. 7, 1922.

Application filed March 23, 1921. Serial No. 454,700.

To all whom it may concern:

Be it known that I, ALBERT W. ERICKSON, a citizen of the United States, and residing in New York city, in the county and State 5 of New York, have invented certain new and useful Improvements in Printing Rules, of which the following is a clear and exact description, reference being had to the accompanying drawings, forming part of this 10 specification.

This invention relates to printing and particularly to tabular and catalog work.

The invention has for an object to save labor, to increase speed and to provide a 15 sure means of producing flawless work.

The invention has for a further object to eliminate abstruse calculations having to do with the placing of dividing rules.

The invention has for a further object 20 to provide a structure such that when the table is dead, the rules can be extracted as quickly or even more quickly than a lead can be pulled and laid for another job.

This invention has for a further object to 25 provide brass rules that are light and inexpensive and that can be cut to any measure and punched for the printing device as easily as could the old leads.

The invention has for a further object the 30 provision of rules which are reversible so that they can be turned to print a thin line or a thick line or parallel lines as desired.

The invention has for a further object a 35 structure such that a very thin line may be printed at the edge of the work so that the printing of a title, heading or other notation may be brought close to the tabular composition.

Other objects will appear as the description 40 proceeds.

Reference is made to the drawings for a 45 detailed description of a preferred embodiment of the invention which is to be taken in connection with the specification as a part thereof in which

Figure 1 is a perspective view with the parts broken away from one another to show how the rules are placed in position.

Figure 2 is a plan view with the rules 50 locked in position.

Figure 3 is a section taken on the line 3—3 of Figure 2 looking in the direction of the arrows and showing a side view of one

of the rules and of the end slugs for locking the slugs and the rules in position. 55

Figure 4 is a sectional view taken on the line 4—4 of Figure 2 showing the two short rules and the means for locking them in position.

Figure 5 is a section taken on the line 5—5 of the Figure 2 looking in the direction of the arrows showing how the grooves are mounted in the slots and end grooves. 60

Figure 6 is a section taken on the line 6—6 of Figure 2 looking in the direction 65 of the arrows.

Figure 7 is a section on the line 7—7 of Figure 2 looking in the direction of the arrows.

Figure 8 shows one of the leading slugs. 70

Figure 9 shows a type metal close-up rule.

Figure 10 shows one of the brass rules used for the column lines in the printing form.

Referring to the drawings, the end slugs 75 1 and 2 are positioned with the grooves 3 and 4 facing each other. The end slug 1 has a ridge 5 and the end slug 2 a ridge 6 which respectively will serve to print the horizontal transverse lines across the bottom and 80 the top of the table. Between the end slugs which serve to lock the printing slugs in position are placed the full width printing slugs 7 and the short width printing slugs 8. 85

It is readily understood by those skilled 90 in the art that whenever a subheading is used in tabular composition short width or part width slugs are required. These slugs are of the same width as the subheading slugs 10. Each of the printing slugs is 6 95 points thick. It is, of course, desired to print a horizontal line in the table both above and below the subheading title. For this purpose rules made of type metal 11 and 12, each 2 points in thickness are inserted 100 in place of the ordinary printing slugs 7. It is by a simple operation in arithmetic, namely, the thickness of the title heading slug, 6 points, plus the thickness of each of the type metal rules, 2 points, makes a total 100 of 10 points. But the slugs 7 are each 6 points thick and therefore in displacing them a thickness that is a multiple of six points must be provided for. In this case opposite the subheading slug 10 there are 2 105 transverse printing slugs 8 of shorter length

than slugs 7. In order to make an even and uniform thickness a 2 point leading slug is inserted between the printing rule slug 12 and the approximate transverse printing 5 slug 7.

Referring to Figure 10 there is shown one of my improved reversible printing rules 17. This reversible printing rule may have different or the same printing surfaces 19 on 10 top, and 20 on the bottom, so that it may be reversed to print a thick line or a thin line or to print some kind of line with either edge. At both ends of the rules 17 there is provided a rectangular extension 18 which is adapted 15 to be inserted in the grooves 3 and 4 of the end slugs 2 and 1. These rules are cut to the desired length by means of a special tool of my own invention and therefore the rules can be easily prepared. The full 20 length rules 17 fit in grooves 16 which are cut by a special machine invented by me to such a depth that when one edge of each rule rests on the bottom of the corresponding 25 groove the opposite edge of said rule lies in the plane of the printing face. When a 30 subheading 10 is inserted in the tabular composition the rules are not passed the entire length of the form and are cut to lengths so that they terminate at the subheading 35 slug. The rules 21 and 22 are held by means of lugs 18 at one end in the grooves 3 and 4 of the end slugs 1 and 2. In cutting the rectangular extension or lug 18 on the opposite ends of these brass rules 21 and 22, in 35 the case of rules 21 which are held in the apertures 14 in the type metal rule 11, they are cut to a length of 2 points so that they

do not protrude from the opposite side of the rule 11; but in the case of the rules 22 where the extensions 18 must pass over the 40 spaces made by the leading slugs 13, the extensions 18 which lie near the subheading 10 are cut by my special tool to a length of 4 points.

It is apparent that I have invented an improved device for use in tabular composition whereby the rules may be quickly made and quickly and accurately fixed in position in the printing form. They are securely locked whether they extend the entire length 50 of the form or a part length. They are easily reversed so that the rear edge is brought into the printing plane whenever desired.

It is apparent that many modifications 55 may be made in details of my invention without departing from the spirit thereof and therefore I do not wish to limit myself except as in the appended claim.

I claim:

In linotype printing forms, in combination, type slugs with grooves provided transversely of their printing portions, a reversible printing rule to fit within the grooves, the rule having reduced ends, centrally disposed relatively to its height, and opposite end slugs having longitudinally continuous recesses adapted to engage the reduced ends of the rule.

Signed at New York, in the county and 70 State of New York, this 21st day of March, 1921.

ALBERT W. ERICKSON. [L.S.]
